UNITED STATES PATENT OFFICE.

GEORGE L. PRICHARD, OF PORT ARTHUR, TEXAS, ASSIGNOR TO GULF REFINING COMPANY, OF PITTSBURGH, PENNSYLVANIA, A CORPORATION OF TEXAS.

APPARATUS FOR CRACKING OIL.

Original application filed June 22, 1915, Serial No. 35,617. Divided and this application filed November 20, 1920, Serial No. 425,450. Renewed September 18, 1926.

This invention relates to apparatus for cracking oil and it comprises an advantageously vertical still body, agitating and scraping means therein, a shaft for operating the agitating and scraping means, a housing surrounding the shaft at its point of exit from the still body, spaced stuffing boxes on the shaft and means for maintaining a fluid under pressure in the housing 10 chamber; and it further comprises as a new apparatus a still adapted to contain a body of oil, means for heating such still to a high temperature, means for removing vapors therefrom, means for continuously feeding 15 oil thereto, means for maintaining a pressure in the still, a stirrer mechanism adapted to keep granular carbon in suspension in the oil in the still, and to scrape the heated zone of the still, such stirring mechanism including 20 a shaft adapted to receive power, journaling means on the still for the reception of the shaft and fluid cooled cooling and sealing means inclosing such journal means; all as more fully hereinafter set forth and as 25 claimed.

When heavy petroleum oils, such as gas oils, petroleum residua, etc. are heated to a high temperature say above 600 or 650° F., they break down with production of lighter 30 oils, such as kerosene or gasoline; this being the well known cracking process. The action is facilitated by operating under pressure. The effects of pressure upon the nature of the reactions are not well understood; it has apparently other actions than 35 that of merely raising the boiling point of the oil. Cracking has been performed in many types of apparatus but on a practical scale mainly in unobstructed stills externally 40 heated. In the cracking operation, aside from the formation of the lighter products stated, there is always a deposition of carbon and this carbon is in a hard, flinty form. It deposits on the heated portion of the still 45 as a coherent, dense incrustation and not only is its deposition a source of grave inconvenience and expense, since it is hard to remove from the heated portion of the still and causes that portion of the still to burn 50 through, but it also impedes the operation by impeding the supply of heat. I have found that it also exercises another action; that its presence has a marked influence upon the progress of the invention. This car-

bon has a catalytic influence in causing the 55 deposition of more carbon, and it may easily be perceived from the fact that newly depositing carbon invariably forms on previously deposited carbon. The carbon layer cohering to the heating element steadily 60 builds up, newly formed carbon cohering to that already in existence. The net result is a hard dense layer covering the heating element; and where this heating element is the bottom of the still the still bottom fills up 65 and the plates are apt to buckle and warp.

In the ordinary operation therefore, considering a body of oil under cracking distillation in a steel or iron still heated from the bottom, it will be seen that the oil in the bottom layer is subjected to different influences 70 from that in the top layer in that the oil in the bottom layer is not only subjected to more heat, since it is next the heating element which is hotter than the body of oil, 75 but it is in contact with carbon which is exercising a catalytic effect. The top of the oil body, on the other hand, is cracking under a more uniform and lower heat and substantially in the absence of carbon. Carbon 80 does not appear to form to any great extent save next the heating element, that is, next iron, or next previously formed carbon.

I have found that in cracking oils I can produce very much more uniform results 85 and at the same time attain considerable economies in operation by providing stirring mechanism in the still adapted to produce a constant dissemination of granular carbon or coke through the body of oil. In so doing not only does the stirring keep the temperature of the oil body much more uniform but I find that the coke tends to form in small granules which do not adhere to the 90 heating elements to such an extent as is usual. By keeping these coke granules separate and, as far as possible, uniformly distributed throughout the body of oil, the newly formed carbon or coke tends to deposit on that already in existence; that is, it deposits on the granules or forms new granules. These granules being in every portion of the 95 oil body, the cracking operation goes on much more uniformly and rapidly than is usually the case. Substantially I may say I am 100 performing my cracking throughout the entire body of the oil, instead of, very largely, 105 in the layers immediately in contact with the

heating elements. The stirring keeps all the oil uniform in temperature; i. e., the whole body of oil is at the high cracking temperature instead of, mainly, the layer of oil next to the heating elements. And it is maintained full of catalytically acting carbon. With the opportunity for the deposition of the excess carbon formed by the presence of the catalytically acting coke granules, there is a greater tendency toward the production of saturated gasoline; something which is highly desirable.

It is however substantially impossible to use a stirring mechanism of any kind in the ordinary type of stills and particularly when the still is run under pressure. The walls of a still must be vapor-tight while at the same time the temperatures of oil distillation in the cracking operation are very high. It is difficult to furnish a tight gland or a journal for rotating power-driven elements of a stirrer which shall be both vapor-tight and uniform in engagement at all temperatures. As stated, a cracking still is ordinarily run at temperatures in excess of 600° F. These difficulties are accentuated when the still is run under pressure; say, a pressure of 80 pounds to 300 pounds.

I have however found that by a particular structure of the top of the still, I can maintain the portion of the still body carrying the journaling means and the journaling means themselves at a lower and more convenient temperature than that prevailing in the body of the still. And with these means I can produce a journaling of the shaft which will be tight against liquid and vapor and which is not affected by the temperature of the still; in which the journal bearing has about the same engagement with the shaft whatever the temperature of the still and of the liquid which the shaft-carried means is agitating.

In the accompanying illustration I have shown, more or less diagrammatically, an embodiment of my invention. In this structure

Fig. 1 is a view, partly in elevation and partly in vertical section, of a still under this invention;

Fig. 2 is a detailed view on an enlarged scale of the still and stirring means; and

Fig. 3 is a diagrammatical showing of a chain stirrer.

In this showing element 1 is a still of cylindrical or other shape and made of any suitable material, such as steel boiler plate. It may be provided with external or bottom firing means 2 of any suitable type. At its top it is provided with vapor outlet 3 leading to an air cooled chamber 4. From this chamber vapor line 5 passes to another air cooled chamber 6 beyond which is outlet 7 provided with loaded valve 8. Conduit 9 takes the vapors to diagrammatically shown

condensing apparatus 10 which may be of any usual type. Beyond the condenser is a valve 11 which may be used to cause still pressure to prevail throughout the condenser. Conduit 12 leads into release chamber 13 provided with gage glasses 14 and valved gas pipe 15. This gas release pipe may lead to any suitable means for utilizing the gas (not shown). Liquid is removed from this tank through valve draw-off 16. The air cooled condensing chambers are provided with runback 17 communicating with both and leading back into the still.

The bottom 18 of the still may be, as shown, somewhat dished. Across the still at a distance from the bottom is an angle iron bracket 19 supporting a thrust collar, 20. Through this thrust collar passes vertical shaft 21 carrying cross bars 22 to which may be connected chains 23 (see Fig. 3) adapted to sweep the bottom or heated zone of the still. On the top of the still is plate 24 forming the support for the cooled bearing. On this plate is mounted casing 25. Elements 24 and 25 may be a single casing. This casing is provided with inlet 26 for cooling fluid and outlet 27. This outlet passes to cooling coil 28 in chamber 29 which may contain water or the like and thence to pump 30 which returns cooled fluid to the stated casing. At its top this casing is provided with cover plate 31. As shown, this cover plate is secured in position by bolts and is gasketed to make it removable; but it may be riveted into place. Within the casing is bearing 32 through which the shaft passes. Metallic packing 33 held in place by element 34 is provided forming a stuffing box. The cover plate carries another bearing 35 also having a good packing 36 around the shaft forming a second stuffing box spaced from the first stuffing box. At the bottom the still is provided with a draw-off 37 for tar and granular coke. Valve 38 mounted on rod 39 serves to control discharge of tar to the exit 40. The valve rod passes through tubular casing 41 having a screw stuffing box 42 and is operated by lever 43. Motion is given the stirring mechanism by gears 44 from shaft 45. Cage 46 may be provided. Outlet 47 (see Fig. 1) may be provided leading to a safety valve (not shown). The still may be charged either continuously or from time to time through charging line 48.

In the use of this structure, the still is charged to any desired height with the oil to be cracked or distilled, such as gas oil, petroleum residuum, heavy crude oils, etc. Or a charge of ordinary crude may be placed in the still and distilled until the lighter oils are distilled. If the pressure of the still is not desired in the condenser, valve 8 may be used and valve 11 left open; but if it is desired that the still pressure extend through

the condenser, valve 11 may be closed to an appropriate degree and valve 8 kept open. In either event heating is continued until gage 46 shows the desired amount of pressure within the still. During this heating the stirrer is kept in steady movement over the heated zone, scraping the carbon from the heated zone as it develops. When carbon begins to develop, instead of baking on and adhering to the heating elements, it is removed and forms loose granular material which is kept circulating through the body of oil. When the desired amount of pressure is attained, valve 8 or valve 11 may be opened to the desired extent and distillation under pressure begun. The pressure is kept at the desired point by adjustment of the firing means and of the reducing valve used. While I may use from 80 to 300 pounds pressure, I have found a pressure of about 95 pounds to be most advantageous. During this heating operation oil is kept flowing into the casing 25 through inlet 26 and is discharged through outlet 27. This flow of oil keeps the whole bearing at a comparatively low temperature irrespective of the heat in the still. The influence of expansion being removed, a tight joint can be maintained while operating the stirrer. If desired, the oil may be introduced through 26 at a pressure equivalent to that prevailing in the still. If the oil is the same character as that under distillation, it may be maintained at a somewhat higher pressure so as to make leakage inward. In any event, because of the double bearing means 32 and 35, leakage is not to be feared.

The stirrer may advantageously be kept going at a rate of about 30 revolutions per minute.

In lieu of using oil as a cooling means in the journal sealing device 9, any other cooling medium such as water, glycerin, etc., may be used but I regard oil as being, for many reasons, the best material.

The oil flowing through the casing 25 may be kept at any temperature desired.

When the distillation has gone to the desired extent, lever 43 may be lifted, withdrawing plug 38 and allowing the tar and cokey carbon in the still to go to exit through 37. The operation of this still may be continuous, discontinuous and semi-continuous. Where it is desired to introduce oil throughout the distillation this may be done through the inlet 48, (see Fig. 1).

When the chain is used as is shown in Fig. 3 it should advantageously be arranged to sweep the heated zone of the still and assist the stirrer in loosening any adhering carbon.

This application is a division of my prior application Serial No. 35,617, filed June 22, 1915.

What I claim is:

1. An apparatus for treating oil under pressure comprising a still, a movable stirrer therein, an actuating shaft extending outside of the still, a housing chamber surrounding the shaft at its point of exit from the still, spaced stuffing boxes on the shaft, one such stuffing box being located in the housing chamber and the other outside thereof, and means for maintaining cooled fluid under pressure in the housing chamber and around the stuffing box located therein. 75

2. An apparatus for treating oil under pressure comprising a still, a movable stirrer therein, an actuating shaft extending outside of the still, a housing chamber surrounding the shaft at its point of exit from the still, spaced stuffing boxes on the shaft, one of said stuffing boxes being located in the housing chamber and the other being located outside thereof, and means for circulating cooled oil through the housing chamber and around the stuffing box therein and for maintaining a fluid pressure in the housing chamber equal to or greater than that existing within the still. 90

3. An apparatus for cracking oil comprising a still, heating means for a portion thereof, stirring means operating in proximity to the heated portion of the still to remove deposited carbon therefrom and to keep it in suspension in the oil in the still, a shaft for operating said stirring means, a stuffing box for said shaft, a chamber surrounding said stuffing box, means for circulating oil through said chamber and around said stuffing box, and another stuffing box for the shaft outside of said chamber, together with means for operating said shaft. 100

4. In an oil still adapted to work under high pressure, a still body having a top, rotary stirring mechanism within the still, a shaft for operating said mechanism passing through said top, a bearing for said shaft on said top, a closed housing surrounding said bearing, a bearing for the housing through which the said shaft extends, means for rotating the shaft, and means for circulating a cooling fluid through said housing and around the stuffing box therein. 110

5. In an oil still adapted to work under high pressure, a vertical casing, a stirring device mounted to sweep the bottom of the casing, a shaft for said device, a cross-bar and thrust collar holding said shaft at a point above the bottom, a top for the casing, a journal for said shaft mounted on said top, a liquid-cooled housing surrounding said journal and another journal for said shaft mounted upon said housing. 115 120 125

In testimony whereof, I have hereunto affixed my signature.

GEORGE L. PRICHARD.
